The ornamental design for a pet grooming glove, as shown and described.

DESCRIPTION

FIG. 1 is a front perspective view of a pet grooming glove, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the pet grooming glove shown in FIG. 1, shown with the left glove in broken lines, in an environment of use; and,

FIG. 10 is an enlarged detail view of area 10 in FIG. 1.

The long dash-dot broken lines in FIGS. 1 and 10 show the boundaries of the enlargement shown in FIG. 10 and form no part of the claimed design. The short dash-dash broken lines showing of a left hand glove in FIG. 9 depict environmental subject matter and forms no part of the claimed design. All remaining short dash-dash broken lines in FIGS. 1-10 depict portions of the pet grooming glove that form no part of the claimed design.
